UNITED STATES PATENT OFFICE.

JAMES F. McELROY, OF ALBANY, NEW YORK, ASSIGNOR TO CONSOLIDATED CAR HEATING COMPANY, A CORPORATION OF WEST VIRGINIA.

SWITCH.

1,023,264.

Specification of Letters Patent. Patented Apr. 16, 1912.

Application filed August 8, 1908. Serial No. 447,510.

To all whom it may concern:

Be it known that I, JAMES F. McELROY, a citizen of the United States, and a resident of the city of Albany, State of New York, 5 have invented certain new and useful Improvements in Switches, of which the following is a full, clear, and complete disclosure.

This invention relates to the class of overload or cut-out switches for electric circuits, 10 and the object thereof is to produce a switch which will break the circuit when any abnormal condition exists in the circuit, such as a ground or short circuit, but which will not be operated by other sudden increases in 15 the amount of current flowing, such as when the devices operated by the current in such circuit are being started up, unless so described.

My improved switch is particularly adapted 20 for circuits in which heating elements are included, such as heating elements for supplying heat to steam boilers for the generation of steam for heating purposes and as one illustration I have shown this application 25 of the invention.

Boilers such as those just referred to are particularly adapted to the heating of railroad trains drawn by electric locomotives, and where the boiler is located on the locomotive 30 so that the steam heating devices already installed in railroad cars previously drawn by steam locomotives may be used. This system of heating by steam generated through the action of electric current flowing 35 through electric heaters forms no part of my present invention and is merely shown to illustrate one use for that invention.

As will be seen from Fig. 1 of the drawing, 40 the heaters shown consist of metallic tubes adapted to carry an electric current, and located within the boiler tubes or flues but not contacting electrically therewith. The surfaces of these parts are ordinarily 45 separated only by about five-eighths of an inch of air space, and under abnormal or accidental conditions, the current might pass from the heating tube to the metal of the boiler, thereby causing a short circuit or 50 ground, it being understood that the metal of the boiler is grounded because it is carried on the metallic frame of a car or locomotive.

In overload switches of the style previously 55 used with motors on electric cars and

with such apparatus as an electrically heated boiler, the switch is intended to prevent an overload of current in case any accident happens to the apparatus, such, for example, as a ground or short-circuit. It is always desirable to open a circuit through any translating device in case a ground occurs, and such overload switches have generally been arranged so that the controlling magnet will carry the maximum current without releasing the switch when the current is acting normally, but when the ground occurs the extra current thereby produced is supposed to operate the magnet and open the circuit. However, when a device like 70 an electric motor is used, whose starting current is large compared with the ordinary normally running current, the overload switch heretofore employed must be adjusted so that the maximum current necessary for starting or running the motor will be carried without operating the switch, and on the other hand so that an excessive increase of the current, due to grounding, 75 shall operate the switch to open it. When 80 electric heaters having a large heat coefficient are employed in the circuit, there is always a heavy rush of the current through the heater until the same becomes heated up and its resistance thereby increased. An 85 overload switch of the prior kind must therefore be adjusted so as to carry approximately two and one-half times the normal current, and so that the rush of the current through the heating element when it is 90 first started will not open the circuit. The 95 overload switch which forms the subject of my present application, is, on the contrary, so devised as not to open with any current however large that may be sent through the heaters, but to open only when a ground or short-circuit takes place in some part of the apparatus and by reason of the fact that the ground or short-circuit establishes a condition different from that 100 which would be established by a mere increase in the total current.

For a full, clear and exact description of that one form of my invention which I at present deem preferable, reference may be had to the accompanying drawings forming a part of this application, in which—

Figure 1 shows the boiler with the heating elements therein, and shown partly in section, said boiler being electrically con-

nected to my improved overload switch shown in perspective; Figs. 2 and 3 are dia-
grammatic views showing my improved
switch connected respectively with a heat-
ing device or boiler and with an electric
motor; Fig. 4 shows a slight modification
and Fig. 5 a diagram thereof.

Referring to the drawings, the numeral 1,
Fig. 1, indicates the casing of a boiler; 2 the
boiler tubes; 3 the heating elements therein;
4 the insulators at the end of the tubes for
locating and holding the heaters in posi-
tion; 5 the connectors for connecting the
heating elements 3 in series; and 6 and 7
15 indicate the leads connecting the heating
elements with the overload switch. The
overload switch comprises (see Figs. 1 and
4) a base 8 upon which are mounted the
usual stationary contact or strips 9 of the
20 usual or suitable material, such as carbon,
and the movable contact strips 10 carried on
a yoke 11. The yoke 11 is also provided
with the usual metallic connecting blades 12
25 which enter the flexible contact jaws 13,
also carried by the base and electrically
connected with the strips 9. The yoke 11 is
carried on an arm 40 pivoted at 42 and
contacts with the spring 14 for forcing the
arm 40 outward when the switch is released.
30 An elastic buffer 144 is provided for lessening
the upward blow of the arm as the
switch opens and retaining it in its open
position. A projection 15 on the yoke 11 is
adapted to engage a pivoted latch or pawl
35 16, which carries the armature 17. Oppo-
site the armature 17 is placed the core 18
upon which are several turns of wire forming
two coils as indicated in 19 and 20,
wound in opposite directions, and included
40 respectively in the leads 6 and 7 from and
to the elements 3. Upon the latch 16 there
may be mounted a small weight 21 for vary-
ing the sensitiveness of the overload switch.
This weight may be entirely omitted in case
45 it is desirable that the switch shall be very
sensitive.

The numeral 22 indicates the third rail or
other stationary conductor for supplying
current to the apparatus, and 23 indicates
50 the contact shoe coöperating therewith.
The lead 24 terminates at the connector 25
which is electrically connected with one set
of the stationary contact strips 9 and 13.
Connector 26 is electrically connected with
55 the opposite set of contact strips 9 and 13,
and when the yoke 11 is in operative posi-
tion between the two sets of contact strips
9 and 13, the circuit is closed. The con-
nector 26 is connected with the lead 27 form-
60 ing one end of the coil 20 and the other end
of the coil 20 is connected with the lead 7
supplying current to the heating elements 3.
The lead 6 is connected to one end of the
coil 19, and the other end of said coil 19 is
65 connected with the lead 28 passing to the

return conductor, conventionally indicated
as the ground 29, connector 30 being inter-
posed for this purpose.

When the switch is closed the current
from the third rail enters through the shoe
70 23, lead 24, one set of stationary contact
elements 9 and 13, one set of movable con-
tact elements 10 and 12, the yoke 11, the op-
posite set of movable contact elements 10
75 and 12, the other set of stationary contact
elements 9 and 13, the connector 26, coil
20, the lead 7, the heating elements 3, the
lead 6, the coil 19, the lead 28 to the re-
turn 29. Since the current passes through
the coils 19 and 20 in opposite directions,
80 they tend to neutralize each other when
the normal or even the heavy starting cur-
rent, however great it may be, is passing
through the heaters, but should a ground
take place from any of the parts beyond the
85 coil 20 as indicated, for example, at 54 in
Fig. 5 the current in one of the coils will be
increased since that coil will be in series
with the ground and the magnetism which
was before balanced, will be lessened or
90 eliminated in the other coil which has been
shunted by the ground and the latch oper-
ated to open the switch. This arrangement
enables the switch to be opened when a
95 ground occurs even if the ground should
not cause any increase of the total current
from the third rail or stationary conductor
from the apparatus. It will thus be seen
that I have provided a switch which does
not require an abnormally large current to
100 operate it, but operates through a division
of the current supplied to the heating ele-
ments or motor, such as in the case of a
ground, the current being diverted directly
105 from the grounding point to the ground or
return conductor without passing through
one of the coils of the switch.

In Fig. 3 the numeral 31 indicates an elec-
tric motor which is controlled in the same
manner as the heating elements in the boiler
110 1, shown in Figs. 1 and 2. In Figs. 2 and 3
the movable element of the switch is indi-
cated by the numeral 32, and the stationary
elements by the numerals 34 and 35, the
spring for operating the switch being indi-
115 cated by the numeral 36. The other parts
in these figures corresponding to Fig. 1 are
indicated by the same reference numerals as
in Fig. 1.

As shown in Figs. 4 and 5, the neutralizer
120 coil 19 which is shunted by the ground, may
oppose coil 20 mechanically, as well as mag-
netically. Thus in Fig. 4 the latch 16 is
mounted on a rod 50 and normally held by
spring 52 in engagement with projection 15
125 on yoke 11, the longitudinal play of rod 50
being limited by collars 53, 53'. The pull
of coil 20 on rod 50, against the tension of
spring 52 is neutralized by the contrary pull
of coil 19. When, however, coil 19 is shunted
130

by a ground in the protected apparatus, it lets go of the rod which then responds to the pull of coil 20, which is in series with the ground, and the switch is released. The 5 collar 53 serves to limit the motion of the core when the conditions are normal. The end portions 50' of said core are made of non-magnetic material.

While the arrangement above described 10 is one that illustrates the principle of a cut out switch provided with a neutralizing coil that normally opposes (either magnetically or mechanically) the operating coil of the switch, but lets go in the event of a ground 15 or short-circuit in the apparatus, yet the same principle may be also applied to a switch that will respond, like an ordinary cut-out to an excess of current in the apparatus, while still retaining the quality and 20 characteristic above described. Thus if the coil 20 has one or more extra turns, as shown in Fig. 3, it will have an excess of power over coil 19 proportional to the product of the number of extra turns by the amperes of 25 current. If, for example, there is one extra turn and the normal or satisfactory current which is below the responding point of the cut-out is two hundred amperes, then the excess power will be two hundred ampere turns 30 and the adjustment may be such that an excess of this amount will not cause the cut-out to act. If, however, the current exceeds this value, the switch will respond and open the current. At the same time an accidental 35 ground in the apparatus will short-circuit coil 19 and coil 20 will then act by removal of the opposition of coil 19, instead of by excess current in its supernumerary turn or turns.

40 Having thus described my invention, I do not wish to be understood as being limited to the exact details of construction or arrangement of parts set forth, for various changes may be made in my invention by

persons skilled in the art without departing 45 from the spirit and scope thereof.

What I claim and desire to secure by Letters Patent is:

1. A switch comprising a core having coils traversed by the current, the coils exerting 50 a force normally in opposition, said coils being responsive to an excess of current and also responsive to the shunting of the current through one of the coils to the ground.

2. In a cut-out switch, means for opening 55 said switch comprising current-carrying devices of unequal force and responsive to an excess of current, and also responsive to the shunting of the current through one of said devices by a ground. 60

3. In combination with a translating device, a cut out switch having coils traversed by the current passing through said device, one of said coils exerting a force counter-balancing a fraction of the force of the other 65 coil and said coils being responsive to an excess of current, and also responsive to the shunting of the current through one of the coils by ground.

4. In combination with a translating device, a cut out switch having unequal differential coils traversed by the current passing through said device, said coils being responsive to an excess of current, and also responsive to the shunting of the current through 75 one of said devices by a ground. 70

5. In a cut-out switch, differential controlling coils in series and normally inactive upon said switch, one coil having a greater number of turns than the other, and a translating device located in the circuit between 80 said coils.

Signed at Albany, county of Albany, State of New York, on the 6th day of Aug., 1908.

JAMES F. McELROY.
